(57) **CLAIM**

The ornamental design for a lobed IV, arterial and midline catheter securement device, as shown and described.

DESCRIPTION

FIG. 1 is a perspective view of the lobed IV, arterial and midline catheter securement device showing my new design, shown with release layers partially opened.

FIG. 2 is a top view of the device with the release layers shown in the closed position.

FIG. 3 is a bottom view of the device with the release layers shown in the closed position.

FIG. 4 is a front view of the device with the release layers shown in the closed position.

FIG. 5 is a rear view of the device with the release layers shown in the closed position.

FIG. 6 is a left side view of the device with the release layers shown in the closed position.

FIG. 7 is a right side view of the device with the release layers shown in the closed position.

FIG. 8 is a top view of the device with the release layers removed.

FIG. 9 is a bottom view of the device with the release layers removed.

FIG. 10 is a front view of the device with the release layers removed.

FIG. 11 is a rear view of the device with the release layers removed.

FIG. 12 is a left side view of the device with the release layers removed.

FIG. 13 is a right side view of the device with the release layers removed; and,

FIG. 14 is a top view of the device with the release layers removed, shown in the folded position.
